UNITED STATES PATENT OFFICE.

JAMES G. BLUNT, OF SCHENECTADY, NEW YORK.

LOCOMOTIVE GRATE SHAKER.

Application filed February 21, 1921. Serial No. 446,766.

To all whom it may concern:

Be it known that I, JAMES G. BLUNT, of Schenectady, in the county of Schenectady and State of New York, have invented a certain new and useful Improvement in Locomotive Grate Shakers, of which improvement the following is a specification.

My invention relates to means for shaking or rocking the grates of locomotive fireboxes, as may, from time to time, be found necessary or desirable in order to clear them of clinkers and cinders, and facilitate the access of air to support combustion of the fuel. The object of my invention is to provide a mechanism of the above stated type which will be simple and inexpensive as to construction and maintenance, and operable, either by fluid pressure or manually, in such manner as to impart any desired degree of angular movement to the grate bars, from their normal level or fire supporting position, up to the maximum degree of angular position which they are capable of assuming for the purpose of dumping all or any desired portion of the fuel which rests upon them.

The improvement claimed is hereinafter fully set forth:

In the accompanying drawings: Figure 1 is a view, in elevation, of the major portion 30 of the back head of a locomotive boiler, illustrating an application of my invention, with a single operating cylinder, located in the vertical longitudinal central plane of the boiler; Fig. 2, a similar view, illustrating an application, in which two mechanisms, only 35 one of which is shown, are disposed on opposite sides of said central plane; Fig. 3, a partial section through the firebox, on said central plane, with the grate shaker mechanism in side elevation; Fig. 4, a longitudinal central section through the operating valve and its chest, with the operating lever and connections in elevation; Fig. 5, an end view, in elevation, of the operating valve chest, 40 with the operating lever and connections in elevation, at a right angle to Fig. 4; Fig. 6, a rear view, in elevation, of the operating valve chest, with the cap detached; Fig. 7, a similar view of the operating valve; Fig. 8, 45 a central section through the same; Fig. 9, a longitudinal central section through the operating cylinder; Fig. 10, a partial plan view thereof, with the superposed disconnecting mechanisms shown partly in plan and partly

in section; Fig. 11, a view, the left hand half 55 of which is an elevation of one of the disconnecting mechanisms, and the right hand half, a longitudinal central section through the other disconnecting mechanism and a transverse section through the operating cylinder; Fig. 12, a longitudinal section through the operating lever, and transverse section through its fulcrum pin, Figs. 13, 14 and 15 are longitudinal sections through the operating cylinder, showing the piston, actuating 60 lever, valve, and connections between the latter and the piston, in different positions.

My invention is specially designed for application in connection with the rocking grates of locomotive boilers, and is, therefore, herein exemplified as applied in a locomotive boiler having such a grate. It will, however, be obvious that it is not limited, in application, to boilers of this type, and that it may be employed, without variation of structural or operative principle, on stationary and marine boilers which are provided with rocking grates.

In the practice of my invention, referring descriptively to the specific embodiment 80 thereof which is herein exemplified, a horizontal operating cylinder, 1, one or more of which may be used, as conditions may require, is suitably supported upon a locomotive engine, preferably a short distance in rear of 85 the firebox, 2, or in any other convenient location where it will not interfere with the movements of the fireman. The opposite ends of the operating cylinder are closed by heads, 1^a, and fluid pressure supply and discharge pipes, 1^b, 1^c, lead from opposite ends of the cylinder to the casing of an operating valve hereinafter described.

The firebox, 2, is provided with a grate, 3, which may be of any suitable and preferred 90 form of the rocking type, and as it does not, in and of itself, form part of my present invention, it will not be herein at length set forth. In connection with grates of comparatively large areas, which are now generally in use, a plurality of operating cylinders, located in planes on opposite sides of the vertical longitudinal central plane of the boiler, is preferably applied, the pistons of said cylinders independently actuating 100 different sets of grate bars. The cylinders and connected actuating mechanisms are, however, substantially similar, in construc-

tion and operation, as will be understood from the following description of a single mechanism.

Each operating cylinder is fitted with a piston, 4, comprising two suitably packed end heads, connected by interposed side members, in which there is fitted a transverse rocker, 5. An operating lever, 6, is mounted on a fulcrum shaft, 7, extending above, and transversely to, the operating cylinder, 1, in the middle plane of its length, said lever passing through a longitudinal slot in the cylinder and engaging a slot cut to receive it in the rocker, 5. The lever, 6, is extended above its fulcrum shaft and is bifurcated at and adjoining its upper end, as shown in Figs. 11 and 12, in order to be coupled, by a pin, 6^a, to the lower end of a valve closing link, 8, the upper end of which is, in turn, coupled, by a pin, 8^a, to a manually operable valve actuating lever, 9.

A valve casing, 10, which is supported upon a standard, 17, located on, or adjacent to, the operating cylinder, 1, is connected to a reservoir of fluid under pressure, which may be either steam or air, by a supply pipe, 10^a, controlled by a stop valve, 10^b, and is closed by a removable cap, 10^c. The supply and discharge pipes, 1^b, 1^b, of the operating cylinder, are connected to the valve casing, 10, and an exhaust pipe 10^d, leads therefrom to a suitable location of discharge. The supply and exhaust of motive fluid, to and from each of the ends of the operating cylinder, is controlled by an operating valve, 11, vibratable on a face in the valve casing over parts therein communicating with the pipes, 1^b, 1^b and 10^d. Vibratory movement is imparted to the operating valve by the actuating lever, 9, which is journaled on the periphery of the valve casing, through the intermediation of a stem, 12, journaled centrally in the valve casing, and having, on its inner end, a transverse tongue, 12^a, which engages a corresponding slot in the operating valve. A crank arm, 12^b, fixed on the outer end of the stem, 12, carries on its free end, a socket, 12^c, in which a cylindrical block, 12^d, is fitted to turn freely. The closing link, 8, passes freely through the socket and block, and in and by the vibratory movements of the valve actuating lever, 9, to which it is coupled, imparts corresponding movements to the stem, 12, and operating valve, 11. Said valve is held up to its seat by a spring, 11^a, fitting in a central recess in the cap, 10^c, of the casing, and bearing on a cover plate, 11^b, fitting against the top of the valve, and performing the additional function of preventing the abnormal passage of motive fluid from one port to another of the casing, or outwardly therefrom around the stem, 12. The traverse of the operating lever, 9, is limited to the proper degree, by stop pins, 9^a, on its

hub, which are adapted to abut against seats on the sides of a tubular post, 9^b, on the valve chest. The lever, 9, is locked in position when not in use, by a clip, 9^c, pivoted to the post, 9^b, by a bolt, 9^d, and is held in any adjusted position, by a stop, 9^e, fitting in the post, and subject to the outward pressure of a spring 9^f.

The vibratory movements imparted to the operating lever, 6, by the piston of the operating cylinder, are transmitted to the grate bars, through a pair of grate levers, 13, which are formed integral with or rigidly secured to, sleeves, 13^a, which are journaled in bearings, 13^b, on the top of the operating cylinder, 1, and on opposite sides of the lever, 6, towards and from which they are laterally movable, so as to be manually engaged with, or discharged from, said lever, in the manner of a clutch coupling, as from time to time desired. The grate levers are coupled by links, 14, to bars, 14^a, which are, in turn, coupled to the grate bars, 3. Pairs of laterally extending clutch jaws, 6^b, are formed on opposite sides of the operating lever, 6, in position to be engaged by tongues, 13^c, on the inner ends of the sleeves, 13^a, when the latter are moved inwardly for that purpose, and when such engagement of one or both of the sleeves with the lever, 6, is made, the vibratory movements of said lever will be imparted to the corresponding grate lever or levers, 13. The engagement of the sleeves with the lever is effected by eccentrics, 15, journaled in caps 15^b, screwed upon the ends of the fulcrum shaft, 7, and rotated by handles, 15^c. Upon the release of the pressure of the eccentrics, the sleeves, 13^a, are moved outwardly, and disengaged from the lever, 6, by springs, 16, fitted in recesses in the sleeves, surrounding the shaft, 7.

The upper ends of the grate levers, 13, are adapted to be engaged in sockets on the ends of attachable and detachable hand levers, 110 when it is desired to shake the connected sections of the grate by hand.

In the operation of a grate shaking mechanism of the construction substantially as above described, the actuating lever, 9, is manually moved, through a greater or less range of traverse, in accordance with the degree of rocking movement which it is desired to impart to the grates, and, in each movement of the lever, by reason of its connection with the operating valve, 11, through the valve closing link, 8, crank arm, 12^b, and valve stem, 12, it moves said valve into position to admit motive fluid to the piston, 4, of the operating cylinder, thereby effecting a stroke of said piston, the extent of which will be proportionate to the degree of movement imparted to the lever. This movement of the piston will, through the operating lever, 6, and grate levers, 13, rock the grates 120

in one direction. Upon the cessation of the movement of the actuating lever, the movement of the piston will, through the operating lever, 6, valve closing link, 8, crank arm, 12^b, and valve stem, 12, automatically close the operating valve and cut off the supply of motive fluid to the cylinder, 1. The succeeding movement of the actuating lever, in the opposite direction, will correspondingly move the operating valve into position to exhaust from the cylinder the motive fluid which has effected the preceding stroke, and admit fluid for a stroke in the opposite direction, which stroke will be determined by the extent of movement of said lever, and the valve be closed at its termination, as above described.

In Fig. 13, the parts are in central position, both pipes 1^b, 1^b, being connected through the valve 11 with the exhaust pipe, so that there is no pressure on either side of the piston. In Fig. 14, the actuating lever 9 has been moved over to the right for the purpose of causing the piston to be moved in the same direction, the valve 11 having been turned so as to admit pressure to the left hand end of the cylinder, while the right hand end of the cylinder is still connected to the exhaust pipe through pipe 1^b at that end and a groove in the face of the valve. Under the influence of the pressure in the left hand end of the cylinder, as soon as it has built up sufficiently, the piston moves to the position shown in Fig. 15, rocking the operating lever 6, the upper arm of which is swung to the left and, through the valve-closing link 8, turning the valve 11 back into its original position in which it connects both pipes 1^b, 1^b, to the exhaust, leaving the piston stationary. The piston is moved in the other direction by throwing the lever 9 over to the left.

I claim as my invention and desire to secure by Letters Patent:

- 45 1. In a grate-shaking apparatus, the combination of a fluid-pressure operating-cylinder, a piston fitted to reciprocate therein, a fulcrum shaft journalled transversely on said cylinder, an operating-lever pivoted on said shaft and engaging said piston, a grate-operating lever also pivoted on said shaft, and means to clutch said levers together at their pivots.
- 50 2. In a grate-shaking apparatus, the combination of a fluid-pressure operating-cylinder, a piston fitted to reciprocate therein, a fulcrum shaft journalled transversely on
- 55 3. In a grate-shaking apparatus, the combination of a fluid-pressure operating-cylinder, a piston fitted to reciprocate therein, a rocker journalled transversely in said piston, a fulcrum shaft mounted transversely on said cylinder, an operating-lever oscillatable about the axis of said shaft and passing through said rocker, grate-levers also oscillatable about said axis, means to connect said grate-levers at will to said operating-lever at their axes of oscillation, and means 60 to connect said grate-levers to sections of the grate to be rocked.
- 65 4. In a grate-shaking apparatus, the combination of a fluid-pressure operating-cylinder, a piston fitted to reciprocate therein, a rocker journalled transversely in said piston, a fulcrum shaft mounted on said cylinder above and parallel to said rocker, an operating-lever on said fulcrum shaft and engaging said rocker, grate-levers mounted on said fulcrum shaft on each side of said cylinder, means axially movable on said fulcrum shaft to connect and disconnect said grate-levers to and from said operating-lever, and a valve to control the supply and 70 exhaust of fluid to and from said cylinder.
- 75 5. In a grate-shaking apparatus, the combination of an operating cylinder slotted in its center, a piston in said cylinder, a rocker journalled transversely in said piston, a fulcrum shaft on said cylinder above and parallel to said rocker, an operating-lever on said shaft and passing through said slot and said rocker, grate-levers on said shaft, means to move said grate-levers along said 80 shaft to engage them with or disengage them from said operating-lever, a manually openable valve for controlling the supply to and exhaust from the ends of said cylinder, and a link-and-crank connection between the upper arm of said operating-lever and said valve, whereby the piston, in moving towards either end of the cylinder, automatically closes said valve.

JAMES G. BLUNT.
